UNITED STATES PATENT OFFICE.

HARRY PHILLIPS, OF LONDON, ENGLAND, ASSIGNOR TO DENTAL MANUFACTURING COMPANY, LIMITED, OF LONDON, ENGLAND.

SCULLING MACHINE.

Application filed November 10, 1922. Serial No. 600,141.

To all whom it may concern:

Be it known that I, HARRY PHILLIPS, a subject of the King of Great Britain and Ireland, residing at 208 Norbury Crescent, 5 Norbury, London, S. W., England, have invented new and useful Improvements in and Relating to Sculling Machines (on which application has been made for Letters Patent in Great Britain No. 12,535, 10 filed the 3rd May, 1922), of which the following is a specification.

The present invention relates to improvements in sculling machines.

From time to time sculling machines have 15 been introduced for the purpose of training oarsmen. None of these machines have proved satisfactory for the purpose for which they are designed; in no case has it been possible hitherto to design a sculling 20 machine which reproduces the actual conditions found in actual sculling. The pressure upon water of the scull blade should be the same at the beginning as at the end of the stroke. Again the scull members 25 have hitherto been anchored so that it is impossible for the oarsmen to drop their hands at the end of the stroke as must occur under natural conditions.

The present invention is designed to provide 30 a machine in which there is an even resistance throughout the stroke, in which this resistance is adjustable in which the outriggers are carried on a sliding frame which carries a seat sliding thereon, and in which the scull ends slide in rings pivotally 35 mounted on vertically movable members.

In the drawings accompanying this specification—

40 Figure 1 shows a side view.

Figure 2 shows a plan view, and

Figure 3 shows a front view of the complete machine.

Figures 4 and 5 show sectional views of 45 the oil dash-pot.

Figure 6 shows the piston and sliding plug, which normally closes the end of the piston, but is here shown open as during the return stroke of the sculls.

50 Figure 7 shows in section and in outside elevation the columns forming the fixed points to which are pivotally attached the ends of the sculls.

Referring now to Figures 1 to 3, 1 is the 55 sliding frame carrying the seat 2 which can

slide on runners 3. At the other end of the frame is the footboard 4 which is adapted to be moved backward or forward so that it may be adjusted to suit the height of the user of the machine. To the sides 60 of the frame 1 are fixed the outriggers 5, adapted to receive the sculls 6 in pivoted rings 7 as is usual on a boat. Mounted in the bottom of the frame 1 are grooved wheels 8. These wheels run on a rail 9 attached to the base 10 of the machine, thus allowing the frame to slide easily backwards and forwards. The base 10 is conveniently in the form of a cross as shown so that the various parts of the machine 70 may be conveniently mounted. Into the bottom of the movable frame 1 the oil cylinder 11 is fixed so that it moves backwards and forwards with said frame 1. The piston rod 12 is hollow and is fixed by means 75 of a bracket 13 to the front of the base 10 that is behind the user.

Referring now to Figures 4 to 6, the piston rod 12 enters the oil cylinder through a packed gland 14 of usual construction. 80 The other end 40 of the oil cylinder is closed. The piston 15 is in the form of a sleeve and the inner end is closed by a plug 16. This plug is arranged to slide so that on the return stroke it leaves the piston end open and allows free passage for the oil. In the piston wall a convenient number of slots 17 are arranged through which the oil can pass on the return stroke. The piston is mounted on the rod 12 and is attached by pins 188 as shown, or it may be screwed on or otherwise firmly fastened. Inside the hollow piston rod 12 is another rod 18. This is made a good fit in the piston rod 12 so that it may be turned if desired, but so that there can be no oil leakage between the two rods. The end of this rod has flats or grooves formed on it and the plug 16 has a hole of corresponding shape in its centre, so that the plug 16 is 95 guided centrally by the rod 18. A shoulder 19 formed on the end of the rod 18 takes the thrust of a light spring 20 which is provided to ensure the plug 16 returning to its seating in the piston end, on the completion of the return stroke. The rod 18 is conveniently concentrically drilled with an oil passage 21. This communicates with the oil cylinder 11 beyond the inner end of the piston by means of a convenient num- 100 105 110

ber of parts 22. At the other end of the passage 21, a passage 23 is cut through the side of the rod 18 so that it can register with a port 24 in the side of the outer 5 end of the piston. By turning the rod 18 inside the piston rod 12 the port 24 and passage 23 may be brought more or less into register and a layer or smaller channel formed for the oil. The actual total range 10 of rotation of the rod 18 is limited from fully open to fully closed by means of a radial screw or pin 25 (shown in dotted lines on Figure 4) in the rod 18, working in a slot 26 in the piston. On the forward 15 stroke the inner end of the piston is closed by the plug 16 and is kept closed more firmly by the oil pressure. The oil therefore passes the piston through the ports 22, the passages 21 and 23 and the ports 24. This 20 forms a channel of constant high resistance to the oil, the actual resistance of which can be varied by rotating the rod 18 to vary the effective passage between the passage 23 and the port 24 as already described. 25 On the return stroke, the same passage is open to the oil, but in addition the oil passes through the slots 17 in the piston and as soon as the oil pressure rises sufficiently to overcome the pressure of the light spring 30 20, the plug 16 rises from its seating and the oil flows freely through the inner end of the piston. Buffer springs 27 and 28 are provided at both ends of the oil cylinder so as to avoid the shock of a sudden stoppage 35 should the stroke be carried too far. A cup 29 with a suitable screwed stopper is provided for filling the oil cylinder with oil.

Referring now to Figure 7, the fixed fulcrum points consist of a vertical hollow column 30 which is rigidly affixed to the base 10, an inner column 31 slidably arranged and fitting inside the column 30, and ball 32, pivoted on a horizontal axis 40 between trunnions formed at the upper end of the column 31. The ball has a horizontal hole 33 drilled through it perpendicular to the axis on which it is pivoted. In this hole the metal end of the scull fits and slides. The ball 32 is fitted with an oil cup 34 for lubricating the scull end and through suitable passages the trunnion bearings and the column 31. The column 31 is prevented from rising right out of the column 30 by means of a screw 35, the point of which works in an annular groove 36 turned in column 31. The column is thus free to turn or to rise vertically till the shoulder formed by the lower end of 45 the annular groove comes into contact with the screw 35. Owing to the combined pivoting and sliding action of the columns it is obvious that the sculls are constrained to act about the vertical axis of the columns 50 as fulcrums, but are free to rise and fall 55

and slide through the columns to allow for the varying distance between the pivoted rings 7 and the columns during the stroke. The sculls 6 are for the greater part of their length made exactly like the sculls 70 used on a boat, with the usual leather button 37 to prevent the scull from sliding through the pivoted rings 7. In place of blades, however, they are provided with metal rods 38, which fit, yet slide freely in, 75 the holes 33 in the ball tops 32 of the columns. It will be seen therefore that the whole arrangement of the sculls allows of their being used exactly as they are used in sculling a boat. The whole machine may be fixed to the floor or it may be kept steady by its own weight, and attached to a wall or vertical post through a shock absorbing spring 39.

What I claim is:—

1. A sculling machine comprising a base, a frame slidably mounted thereon, a foot-board, and outriggers carried in said frame, a seat slidably mounted on said frame so as to move along said frame during the forward movement of the latter, scull members pivoted on the outriggers, the outer ends of the scull members sliding in fulcrum members attached to the base, and means whereby said fulcrum members are adapted to move vertically and rotate about vertical and horizontal axes. 90

2. A sculling machine comprising a base, a frame slidably mounted thereon, a foot-board and outriggers carried in said frame, 100 a seat slidably mounted on said frame so as to move along said frame during the forward movement of the latter, scull members pivoted on the outriggers, the outer ends of the scull members sliding in fulcrum members attached to the base, and means whereby said fulcrum members are adapted to move vertically and rotate about vertical and horizontal axes in combination 105 with a dash-pot producing a constant resistance on the forward stroke and allowing a free return stroke.

3. A sculling machine comprising a base, a frame slidably mounted thereon, a foot-board and outriggers carried in said frame, 115 a seat slidably mounted on said frame so as to move along said frame during the forward movement of the latter, scull members pivoted on the outriggers, the outer ends of the scull members sliding in fulcrum members attached to the base, and means whereby said fulcrum members are adapted to move vertically and rotate about vertical and horizontal axes in combination with a dash-pot producing a constant resistance on 120 the forward stroke and allowing a free return stroke and means for adjusting the resistance produced by the dash-pot. *

4. A sculling machine comprising a base, a frame slidably mounted thereon, a foot- 130

board and outriggers carried on said frame, a seat slidably mounted on said frame so as to move along said frame during the forward movement of the latter, scull members 5 pivoted on the outriggers and at fixed fulcrum points on the base and an oil cylinder rigidly fixed to the sliding frame, a piston within said oil cylinder attached to the base and means whereby the oil can pass the piston 10 ton through a small constant passage on the forward stroke, and freely through a large passage on the return stroke.

5. A sculling machine comprising a base, a frame slidably mounted thereon, a foot- 15 board and outriggers carried on said frame, a seat slidably mounted on said frame so as to move along said frame during the forward movement of the latter, scull members pivoted on the outriggers and at fixed fulcrum points on the base, an oil cylinder rigidly fixed to the sliding frame, a piston within said oil cylinder attached to the base, and means whereby the oil can pass the piston 20 through a small constant passage, on the forward stroke, means for adjusting the said passage and means whereby the oil can pass the piston freely through a large passage on the return stroke.

6. A sculling machine comprising a base, 30 a frame slidably mounted thereon, a foot-board and outriggers carried on said frame, a seat slidably mounted on said frame so as to move along said frame during the forward movement of the latter, scull members 35 pivoted on the outriggers, the outer ends of the scull members sliding in fulcrum members attached to the base and means whereby said fulcrum members are adapted to move vertically and rotate about vertical 40 and horizontal axes, in combination with an oil cylinder rigidly fixed to the sliding frame, a piston within said oil cylinder attached to the base and means whereby the oil can pass the piston through a small 45 constant passage on the forward stroke and freely through a large passage on the return stroke.

7. A sculling machine comprising a base, a frame slidably mounted thereon, a foot- 50 board and outriggers carried on said frame, a seat slidably mounted on said frame so as to move along said frame during the forward movement of the latter, scull members pivoted on the outriggers, the outer ends of 55 the scull members sliding in fulcrum members attached to the base, and means whereby said fulcrum members are adapted to move vertically and rotate about vertical and horizontal axes, in combination with an 60 oil cylinder rigidly fixed to the sliding frame, a piston within said oil cylinder attached to the base, means whereby the oil can pass the piston through a small constant 65 passage on the forward stroke, means for adjusting the said passage and means where-

by the oil can pass the piston freely through a large passage on the return stroke.

8. A sculling machine comprising a base, a frame slidably mounted thereon, a foot-board and outriggers carried on said frame, 70 a seat slidably mounted on said frame so as to move along said frame during the forward movement of the latter, scull members pivoted on said frame, the outer ends of the sculls sliding in fulcrum members attached 75 to the base, and means whereby said fulcrum members are adapted to move vertically and rotate about vertical and horizontal axes, in combination with an oil cylinder rigidly fixed to the sliding frame, the cylinder being 80 closed at one end and provided with a packed gland and an oil filling cup and stopper at the other, containing buffer springs at both ends, a piston rod attached to the base at one end, passing through the 85 packed gland, carrying a sleeve like piston with slotted sides at the other end, said piston working in the oil cylinder, the piston head being formed as a plug slidably mounted on a guide rod and pressed against the 90 piston by a spring, the plug being adapted to act as a non-return valve to allow the oil to pass it on the return stroke, the guide rod having an oil passage in it, connecting with oil ports beyond the piston head and with 95 a passage through the side of the piston at the opposite end of the piston communicating with the interior of the cylinder.

9. A sculling machine comprising a base, a frame slidably mounted thereon, a foot-board and outriggers carried on said frame, a seat slidably mounted on said frame so as to move along said frame during the forward movement of the latter, scull members 100 pivoted on the outriggers, the outer ends of the scull members sliding in fulcrum members attached to the base, and means whereby said fulcrum members are adapted to move vertically and rotate about vertical 105 and horizontal axes, in combination with an oil cylinder rigidly fixed to the sliding frame, the cylinder being closed at one end and provided with a packed gland, an oil filling cup and stopper at the other, containing buffer springs at both ends, a hollow 110 piston rod attached to the base at one end, passing through the packed gland, carrying a sleeve like piston with slotted sides at the other end, said piston working in the oil cylinder, the piston head being formed as a 115 plug slidably mounted on a guide rod and pressed against the piston by a spring, the plug being adapted to act as a non-return valve to allow the oil to pass it on the return stroke, the guide rod having an oil passage 120 in it connecting with oil ports beyond the piston head and with a passage through the side of the piston at the opposite end of the piston, communicating with the interior of the oil cylinder, the guide rod being ex- 125

130

tended back through and beyond the hollow piston rod so as to be rotatable within the piston rod, the rotation thereof adjusting the size of the oil passage through the side 5 of the piston.

10. A sculling machine comprising a base, a frame slidably mounted thereon, a foot-board and outriggers carried on said frame, a seat slidably mounted on said frame so as to move along said frame during the forward movement of the latter, said scull members having their outer ends in the form of metal rods sliding in balls pivoted in trunnion bearings formed in the upper ends of vertical columns capable of vertical movement and rotation about a vertical axis inside hollow columns forming the fixed fulcrum members for the outer ends of the scull members, said hollow columns rigidly fixed to the base, and provided with lubricators and oil passages, in combination with an oil cylinder rigidly fixed to the sliding frame, the cylinder being closed at one end and provided with a packed gland and an oil filling cup and stopper at the other containing buffer springs at both ends, a piston rod attached to the base at one end, passing through the packed gland, carrying a sleeve like piston with slotted sides at the other end, said piston working in the oil cylinder the piston head being formed as a plug slidably mounted on a guide rod and pressed against the piston by a spring, the plug being adapted to act as a non-return valve to allow the oil to pass it on the return stroke, the guide rod having an oil passage in it, connecting with oil ports beyond the piston head and with a passage through the side of the piston at the opposite end of the piston communicating with the interior of the oil cylinder.

11. A sculling machine comprising a base, a frame slidably mounted thereon, a foot-

board and outriggers carried on said frame, a seat slidably mounted on said frame so as to move along said frame during the forward movement of the latter, scull members pivoted on the outriggers, said scull members having their outer ends in the form of metal rods sliding on balls pivoted in trunnion bearings formed in the upper ends of vertical columns capable of vertical movement and rotation about a vertical axis inside hollow columns forming the fixed fulcrum members for the outer ends of the scull members, said hollow columns rigidly fixed to the base, and provided with lubricators and oil passages, in combination with an oil cylinder rigidly fixed to the sliding frame the cylinder being closed at one end and provided with a packed gland, an oil filling cup and stopper at the other, containing buffer springs at both ends, a hollow piston rod attached to the base at one end, passing through the packed gland, carrying a sleeve like piston with slotted sides at the other end, said piston working in the oil cylinder, the piston head being formed as a plug slidably mounted on a guide rod and pressed against the piston by a spring, the plug being adapted to act as an non-return valve to allow the oil to pass it on the return stroke, the guide rod having an oil passage in it, connecting with oil ports beyond the piston head and with a passage through the side of the piston at the opposite end of the piston, communicating with the interior of the oil cylinder, the guide rod being extended back through and beyond the hollow piston rod so as to be rotatable within the piston rod, the rotation thereof adjusting the size of the oil passage through the side of the piston.

In testimony whereof I have signed my name to this specification.

H. PHILLIPS.
